Michael Kelly, ATTORNEY

UNITED STATES PATENT OFFICE.

JAMES P. KELLY, OF NEW YORK, N. Y.

CORD TIP.

1,425,384.

Specification of Letters Patent. Patented Aug. 8, 1922.

Application filed December 24, 1921. Serial No. 524,560.

To all whom it may concern:

Be it known that I, JAMES P. KELLY, a citizen of the United States of America, residing at New York city, New York county, 5 N. Y., have invented a new and useful Cord Tip, of which the following is a specification.

My invention relates to improvements in devices of the character set forth in my Patent #1,392,339, dated October 4, 1921. 10 The main object of my present invention is to provide a simple and inexpensive form of construction, the parts of which may be readily assembled on the end of a cord and securely held in place but readily separable 15 when desired.

In my former patent I have illustrated forms of tips in which there are central and lateral gripping members.

My present invention contemplates the use 20 of a sleeve and a clamping member with a head provided with a recess or perforation into which an instrument such as a pin may be inserted for holding the head while the sleeve is pulled along the cord so as to separate the parts. The clamping member may 25 engage the cord in any suitable manner, but I have illustrated herein as one form a particularly simple construction, in which, the clamping member is in the form of a pin adapted to be stuck through the cord transversely and bent over and held by the sleeve.

Fig. 1 is a side view of one form of cord tip embodying improvements of my invention.

35 Fig. 2 is a perspective view showing the sleeve slipped back along the cord.

Fig. 3 is a view of the clamping member before it is bent over.

40 Figs. 4 and 5 are perspective views of other forms of lateral clamping members having instrument receiving recesses in their heads.

45 Fig. 6 is a perspective view of a central tip clamping member with a coiled head and recess.

Fig. 7 is a plan view of another form of clamping member with side jaws and a recess in the head.

50 Fig. 8 is a longitudinal sectional view of another form of cord and tip of my invention.

Fig. 9 shows the parts of another form of tip, the sleeve being in section.

55 The cord or string 10 may be of any suitable material, such, for instance, as braided, twisted, or woven threads such as are com-

monly employed in making shoe strings and the like. The particular cross-section such as round, oval, or flattened is immaterial. The sleeve 11 is in the form of an open ended 60 tube of suitable cross-section, and will usually be of somewhat less transverse internal area than the end of the cord so that it will fit snugly. The clamping member is in the form of a pin having a shank 12 and a head 65 13. The pointed end or tip 14 of the pin is adapted to be stuck through the cord and then bent over as shown in Fig. 2. When the sleeve 11 is pulled out toward the end it compresses the parts 12 and 14 into the sides of 70 the cord and thus increases the gripping effect. The main shank of the pin may be provided with barbs or tongues 15 adapted to stick into the cord and increase the gripping effect. The back or shoulder 16 of the 75 head may be tapered or inclined so as to assist in centering the head with respect to the end of the sleeve 11.

To remove the tip, for instance for the purpose of shortening the cord and reapplying the tip, it is necessary to slide the sleeve 11 along the end of the cord away from the head 13. When the parts are made so as to fit together snugly, this operation of separation is sometimes rather difficult. 85 To facilitate the separation I therefore provide a recess such as 17 into which the point of some instrument such as a pin may be inserted to hold the head and clamping member while the sleeve is slipped back into the 90 position shown in Fig. 2. It will be obvious that the end or tip 14 may then be withdrawn from the cord. To prevent interference with this withdrawal, the end or tip 14 is preferably left smooth. To re-apply 95 the device, the cord is cut at the desired point and the tip 14 of the pin pushed through the cord and bent over as shown in Fig. 2, and the sleeve 11 pulled down to the end against the rear shoulder of the head. This 100 provides a very secure tip which cannot become disengaged accidentally.

In the form shown in Fig. 4 the shank 12' is flattened and adapted to lie against one side of the cord. In this form the barbs or tongues 15' are formed by punching small triangular holes. The recess 17' instead of being entirely in the exposed part of the head may be in the edge of the head so that less of it will be exposed beyond the 110 end of the sleeve when the parts are assembled. As the tapered point of an ordi-

nary pin or needle (not shown) is inserted into the outer part of the recess 17^a it will begin to force the sleeve away from the head.

5 In the form shown in Fig. 5, the barbs or teeth 15^a are formed on the edges of the shank of the clamping member.

The form of device shown in Fig. 6 has a shank 12^a adapted to be inserted into the 10 center of the end of the cord, and the head 13^a is formed by coiling the wire so as to leave an instrument receiving recess 17^a.

The form of device shown in Fig. 7 is formed by bending a piece of wire or strip 15 of material so as to provide two jaws 12^b, one of which is preferably longer than the other so as to facilitate assembly of the sleeve over the jaws. The head portion 13^b is formed so as to provide a recess 17^b for 20 the insertion of a holding instrument.

In the form of device shown in Fig. 8, the clamping or gripping member may be stamped from sheet metal with its head 13^c so shaped as to leave a recess 17^c at the 25 end of the sleeve 11^c.

In the form shown in Fig. 9, the tip 14^d of the shank of the gripping member is long enough to project a bit beyond the end of the sleeve 11^d so that pressure may be 30 applied at this end through the body of the cord to start the separation movement of the sleeve with respect to the gripping member. In this case, the recess 17^d is normally concealed by the end of the sleeve, 35 but is exposed by pressing on the opposite end 14^d so that a pin may be inserted into the recess 17^d for completing the separation movement.

I claim:

40 1. A cord tip device comprising a headed pin with a shank for embracing one side of the end of a cord, said pin having another portion for extending transversely through the cord and a tip portion con-

nected to the transversely extending portion 45 and adapted to embrace the side of the cord opposite the shank of the pin, and a sleeve for embracing the shank and tip of the pin and abutting against the head of the pin.

50 2. A cord tip comprising a member having teeth on one side, a head on one end and a smooth bendable tip, and a sleeve adapted to embrace said member and hold said teeth and said tip in place.

55 3. A cord tip comprising a gripping member with a head at one end and a bendable tip adapted to be inserted through the end of a cord, and a sleeve adapted to slide along the end of the cord for holding said member and its tip in place.

4. A cord tip comprising a gripping member having a head with an instrument receiving recess and a bendable portion adapted to be passed through the end of the cord 60 and a sleeve holding the parts in place.

5. A cord tip comprising a gripping element having a head with a tapered centering shoulder and a toothed shank adapted to lie alongside the end of the cord, and a 70 sleeve adapted to slide along the cord and to hold said shank in place, said sleeve abutting against said tapered shoulder when said parts are assembled.

6. A cord tip comprising a gripping member having a shouldered head with an instrument receiving recess and a sleeve embracing the end of a cord and holding said gripping member in place, said sleeve abutting against said shouldered head.

7. A cord tip comprising a gripping member having a head with a transverse passage for receiving the point of a holding instrument and a shank for engaging the end of a cord, and a sleeve embracing the 85 end of a cord adjacent said head for holding said gripping member in place.

JAMES P. KELLY.
